GAUGE

Lambert R. Pistoles, Wilmington, Del.

Application December 13, 1950, Serial No. 200,572

11 Claims. (Cl. 33—174)

1

This invention relates to gages, and more particularly to gages of the go and no-go type adapted for gaging axial lengths and the like.

In copending applications Serial No. 39,138 and Serial No. 62,737, now Patent 2,610,409, filed August 16, 1948, and November 30, 1948, respectively, there are disclosed gages for measuring lengths of turned members and the like, in which there is a block having a dihedral for engaging a cylindrical surface of the turned member, and a length rod mounted in relation to the dihedral so that such rod will extend parallel to the axis of the cylindrical surface engaged by the dihedral.

The present invention relates to gaging block assemblies, having transversely extending movable blades which may be mounted upon the bar at various positions and in which the blades are moved toward a transverse surface of the work piece to be gaged by mechanism adapted to respond to finger manipulation.

The invention further relates to gaging blade supporting block assemblies which are constructed in two parts and adapted to be secured upon the parallel rod in such manner that accidental shock tending to disturb the setting will render manipulation of the blades impossible. The invention further has to do with mechanism whereby finger manipulation of sliding telescopic-like members in a direction transverse of the rod will effect movement of the gaging blades in a plane transverse to the rod, to bring such blades into gaging relation. The invention is also directed to an assembly of the type referred to which will be accurate, easily set, and readily manipulated.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a side elevation view of a gage of the type described provided with three of such gaging blocks;

Figure 2 is an enlarged top plan view, partly in section, of one of the gaging blocks taken substantially on the line 2—2 of Figure 1;

Figure 3 is an end view of the gaging block, parts of which are shown in section;

2

Figure 4 is a top plan view taken in section substantially on the line 4—4 of Figure 3;

Figure 5 is a top section taken substantially on the line 5—5 of Figure 3;

Figure 6 is a side elevation, with parts broken away, to illustrate the blade translating mechanism; and

Figure 7 is a top sectional view taken substantially on the line 7—7 of Figure 6.

10 In Figure 1, there is shown a gage 10 having an end block 12 provided with a shallow dihedral 16 for engaging a cylindrical surface such as 16 of a work piece to be gaged. The block 12 adjustably supports a gage rod 18 extending parallel with the axis of the cylindrical work piece 16 and the apex line 15 of such dihedral. Where the rod is of extended length, a supporting bracket 20 and guide 22 may be provided. The rod 18 may be secured in the block 12 as by a set screw 24 or any other means, as, for example, shown in the afore-mentioned applications, but in practice such rod will usually be fixed against movement in the dihedral block. The block 12 is provided with sliding plates 26 and 28, such plates having plane surfaces adapted to extend perpendicular to the axis of the rod 18, as also described in said applications. The plate 26 is shown slid to a position whereby the tongue end 30 provides an extended surface 32 adapted 15 to engage the transverse plane end 33 of the work piece 16. Either the plate 26 or the plate 28 may be utilized, when slid in the manner described, to engage a shoulder or end surface on the turned object which may act as a reference plane in 20 the gaging operations to be performed.

25 Mounted on the bar 18 are gaging assemblies 34, 36, and 38, each having gaging blades preferably arranged in pairs as generally indicated at 40, 42 and 44. These blades are movable 30 transversely in the assemblies by mechanism to be described, so as to extend toward the work piece and to gage shouldered surfaces such as 45, 48, and 50, to determine whether such surfaces are accurately located axially with reference to the end surface 33. Each of the gaging assemblies comprises a pair of blocks 52 and 54 having apertures 56 and 58 through which extend the rod 18. Each of the blocks are provided with transversely extending set screws 60 and 62 which are adapted to engage the rod 18 to fix the blocks upon the rod 18 in set position. The block 54 is provided with a plane surface 64 extending transversely to the axis of the bore 58. The block 52 is provided with transverse slots 66 35 and 68 in which are positioned gaging blades 70

and 72. The depth of the slots is slightly less than the width of the blades, so that a certain clearance 74 between the blocks 54 and 52 is required when the blocks are properly set upon the rod 18 to provide sufficient clearance so that the blades 70 and 72 may be freely moved in their respective slots 66 and 68. The blades 70 and 72 are constructed of hardened steel, and their edge surfaces 76 and 78 are true parallel planes and the surface 76 is adapted to bear against the plane surface 64 of the block 54, so that the blades may at all times extend at right angles to the axis of the rod 18.

It will be seen by reference to Figure 6 that when the blades are moved toward the work piece, a gaging surface 80 will be brought into relation with a shoulder 82 on the work piece 16 to be gaged, and that as the blade is projected from the block toward the work piece, it can be quickly ascertained whether the surface 80 will clear the shoulder 82. In practice, for example, the blade 70 will have a surface 80 adapted to just clear the shoulder 82, while the second blade 72 may be provided with a surface several thousandths of an inch laterally disposed in relation to the surface 80, whereby such blade will not clear. It can thus be determined readily by moving the blades toward the work piece whether the shoulder is in the proper axial position by determining that one blade does not clear the shoulder and that the other one does. If both blades clear the shoulder, the shoulder is improperly positioned, and if neither blade clears the shoulder, inaccuracy is likewise indicated.

The block 52 is provided with mechanism for moving the blades 70 and 72 to and from the gaging positions as indicated. In the block, there are mounted opposed finger pieces 84 and 86 formed as right angle extensions upon rack bars 88 and 90. Such rack bars lie in a transverse groove 92 across the top face of the block 52, and are transversely slidable within such groove. The rack bars are held in position by a T-shaped top plate 94 secured as by screws 96, the T-shaped plate affording openings 98 and 100, and stop surfaces 102 and 104, so that the finger pieces 84 and 86 may be pinched or squeezed together, sliding the rack bars until such fingers engage the stop surfaces 102 and 104. Each of the fingers is provided with a boss or stud 106 and 108 axially aligned and about which is positioned a compression return spring 110. The studs 106 and 108 are of such a length as to engage one another when the finger pieces are squeezed together and the spring 110 compressed, limiting the relative movement of the finger pieces prior to their engagement with the stops 102 or 104, if desired.

The rack bar 88 is provided with rack teeth 112 along one edge, and is cut away as at 114 to clear the finger piece 86. The rack bar 90 is provided with teeth 116. Both rack bars are provided with clearances as at 118 and 120 so as not to interfere with the pinions 122 and 124 engaged with the rack bars. The pinions 122 and 124 are so arranged as to effect a stop for the outward movement of the rack bars, a pinion tooth such as 126 engaging the edge of the rack bars beyond the last tooth cut as at 128 to limit movement of the rack bar in one direction. Each of the pinions 122 and 124 are formed on stub shafts 130 and 132 which stub shafts are journaled in bores such as 134.

The block 52 is provided with a deep slot 136 of sufficient width to receive spiral gears such as

138 and 140, which spiral gears are shrunk fit upon the stub shafts 130 and 132, the assembly being effected by positioning the gears 138 and 140 in their slots in alignment with the bores 134, after which the stub shafts 130 and 132 are driven into place. The spiral gears 138 and 140 are provided with teeth such as 142 cut on a 45° angle, and are adapted to engage corresponding rack teeth 144 angularly disposed and formed in the edges 78 of each of the blades 70 and 72.

When the finger pieces are squeezed together, the spiral gears 138 and 140 rotate in opposite directions, as indicated by the arrows shown in Figure 7, and the spiral teeth of such gears and the teeth in the blades 70 and 72 are oppositely cut so that upon rotation of the gears 138 and 140, both blades are driven downwardly through the block in the same direction (see Figure 6).

The block 52 may be reinforced with respect to the slot 136 by positioning of spacer collars 146 and 148 on pins 150 and 152, such spacer collars serving to rigidly space the portions of the block spaced by the slot 136.

The block 54 is provided with a pair of set screws 154 and 156 extending parallel with the bore 58, the set screws being of the socket end type. Such set screws are adapted to bear against the surface 158 of the block 52 and provide a means for accurately spacing the blocks so as to provide the exact amount of clearance necessary for the free movement of the blades 70 and 72 in their respective grooves 66 and 68. In practice, the block 54 will be set upon the rod 18 in such position as to lock the plane surface 64 in the desired gaging position. At this point, the set screw 62 will be tightened to rigidly hold the block 54 in position. Thereafter, the block 52 will be slid toward the block 54 and lightly secured temporarily by the set screw 60, leaving no clearance for the free movement of the blades 70 and 72. Thereafter, adjustments of the set screws 154 and 156 will increase the clearance 74 between the blocks 52 and 54, and as soon as the blades 70 and 72 are sufficiently free for manipulation, the set screw 60 will be tightened so that both blocks 52 and 54 are rigidly secured on the bar 18, and the gage is thus set for operation.

It will be understood that should either of the blocks 50 or 62 of the gage be accidentally struck or subjected to shock, provided set screws 154 and 156 are backed off, such shock will act to move the blocks toward one another and thereby close off the necessary sliding clearance required by the blades 70 and 72, rendering manipulation of the gage impossible. This feature protects the gage from being used when there is a likelihood that its setting has been disturbed by abuse. Likewise, the blades 70 and 72 will not move within their respective slots of deranged or slightly bent by abuse. Thus, the gage, once set, will accurately operate so long as proper use is made of it.

By setting a plurality of assemblies on the rod 18, any combination of surfaces can be quickly inspected for accuracy, the operator holding the dihedral and slide plate in position upon the work piece, with one hand, and quickly squeezing the finger pieces of the gage block assemblies, one after the other, to determine the accuracy of the work piece.

It will readily be seen that by separating the blocks, the blades may be removed and different blades having different end gaging surfaces sub-

stituted, or that upon damage to a blade, a new one may be quickly inserted.

Although a single embodiment of the invention has been illustrated and described, it is to be understood that the invention is not limited thereto. As various changes in the construction and arrangement may be made without departing from the spirit of the invention, as will be apparent to those skilled in the art, reference may be had to the appended claims for a definition of the limits of the invention.

What is claimed is:

1. In a gage of the type described, in combination, a support rod, means for supporting said rod in parallel relation and in fixed axial relation to a turned object having a transverse shoulder axially along its length, a pair of blocks mounted on said rod, said blocks each having an aperture through which said rod extends, and means for frictionally securing said blocks in position upon said rod, one of said blocks having a plane surface at right angles to the axis of said aperture and adapted to face the adjoining block, and the other of said blocks having an adjacent parallel face having a transverse groove therein, a gaging blade having parallel edges slidably disposed in said groove, and with one of said edges in sliding engagement with said plane surface, and means mounted in said last-named block for slidably moving said blade in said groove to project an end of said blade beyond said block toward said object.

2. In a gage of the type described, in combination, a support rod, means for supporting said rod in parallel relation and in fixed axial relation to a turned object having a transverse shoulder axially along its length, a pair of blocks mounted on said rod, said blocks each having an aperture through which said rod extends and means for frictionally securing said blocks in position upon said rod, one of said blocks having a plane surface at right angles to the axis of said aperture and adapted to face the adjoining block, and the other of said blocks having an adjacent parallel face having a transverse groove therein, a gaging blade having parallel edges slidably disposed in said groove, and with one of said edges in sliding engagement with said plane surface, means mounted in said last-named block for slidably moving said blade in said groove to project an end of said blade beyond said block toward said object, and adjustable abutment means in said first-named block extending through said surface and adapted to abut the face of the second block, to set the spacing between said blocks to afford needed clearance for the sliding of said blade.

3. In a gage of the type described, in combination, a support rod, means for supporting said rod in parallel relation and in fixed axial relation to a turned object having a transverse shoulder axially along its length, a pair of blocks mounted on said rod, said blocks each having an aperture through which said rod extends, and means for frictionally securing said blocks in spaced position upon said rod, one of said blocks having a plane surface at right angles to the axis of said aperture and adapted to face the adjoining block, and the other of said blocks having an adjacent face having a pair of parallel transverse grooves arranged on opposite sides of said aperture, gaging blades having parallel edges slidably disposed in said grooves, one of the edges of each blade being in sliding engagement with said plane surface, and means mounted in said last-named

block for slidably moving said blades in said groove to project the ends of said blades beyond said block toward said object.

4. In a gage of the type described, in combination, a support rod, means for supporting said rod in parallel relation and in fixed axial relation to a turned object having a transverse shoulder axially along its length, a pair of blocks mounted on said rod, said blocks each having an aperture through which said rod extends, and means for frictionally securing said blocks in adjacent spaced position upon said rod, one of said blocks having a plane surface at right angles to the axis of said aperture and adapted to face the adjoining block, and the other of said blocks having an adjacent face having a pair of parallel transverse grooves arranged on opposite sides of said apertures, gaging blades having parallel edges slidably disposed in said grooves, with one of the edges of each blade in sliding engagement with said plane surface, means mounted in said last-named block for slidably moving said blades in said groove to project the ends of said blades beyond said block toward said object, and adjustable abutment means in one of said blocks extending parallel with the aperture therein and adapted to abut the adjacent block to set the spacing between the face and surface of said blocks to afford needed clearance for the sliding of said blades.

5. In a gage of the type described, in combination, a support rod, a pair of blocks each having an aperture through which said rod slidably extends, means for securing said blocks in selected positions upon said rod contiguous to one another, one of said blocks having a plane surface extending at right angles to the axis of its aperture, the other of said blocks having a transverse groove in a face thereof adjacent said plane surface, a blade slidably mounted in said groove and having parallel edges spaced apart at least the depth of the groove, one of said edges being adapted to engage said plane surface, and spring-biased manipulating means coacting with said blade mounted on said last-named block for sliding said blade in the groove to project an end thereof from the block for a gaging operation.

6. In a gage of the type described, in combination, a support rod, a pair of blocks each having an aperture through which said rod slidably extends, means for securing said blocks in selected positions upon said rod contiguous to one another, one of said blocks having a plane surface extending at right angles to the axis of its aperture, the other of said blocks having a transverse groove in a face thereof adjacent said plane surface, a blade slidably mounted in said groove, and having parallel edges spaced apart at least the depth of the groove, one of said edges being adapted to engage said plane surface, and the other edge having angularly disposed rack teeth, a spiral toothed rack gear journaled in said latter block and engaging said teeth, and spring-biased manipulating means mounted in said block for rotating said gear.

7. In a gage of the type described, in combination, a support rod, a pair of blocks each having an aperture through which said rod slidably extends, means for securing said blocks in selected positions upon said rod contiguous to one another, one of said blocks having a plane surface extending at right angles to the axis of its aperture, the other of said blocks having a transverse groove in a face thereof adjacent said plane surface, a blade slidably mounted in said groove, and having

parallel edges spaced apart at least the depth of the groove, one of said edges being adapted to engage said plane surface, and the other edge having angularly disposed rack teeth, a spiral toothed rack gear journaled in said latter block and engaging said teeth, said rack gear being mounted on a stub shaft having a rack pinion, and a spring-biased manipulating rack slidably mounted in said block for movement transverse to said stub shaft, said rack drivably engaging 10 said pinion.

8. In a gage of the type described, a block, an aperture extending therethrough, a face extending transversely of the axis of said aperture, a groove in said face to one side of said aperture, 15 a gaging blade having parallel edges spaced apart at least the depth of the groove slidably positioned in said groove and having its inner edge provided with inclined rack teeth, the outer edge of said blade being adapted to engage a true surface of a member mounted contiguous to said face, a slot in said face extending transversely of the groove, a spiral gear located in said slot with its pitch circle traversing the bottom of said groove, a stub shaft for said gear extending parallel with said groove and into said slot, a pinion on said stub shaft, a guideway in said block extending transversely of said stub shaft and adjacent said pinion, and a rack slidably positioned in said guideway in engagement with said pinion.

9. In a gage block, a circular aperture extending therethrough, a plane surface along one face thereof extending at right angles to the axis of said aperture, parallel blade-receiving grooves extending across said surface on either side of said aperture, a deep slot in said surface to one side of said aperture, and extending transversely of said grooves, a stub shaft traversing said slot behind each blade groove, a guideway extending across another face of said block, having an edge thereof extending substantially tangential to both said shafts, spiral gears within said slot on each of said shafts having pitch circles intersecting the base of the respective blade groove forwardly thereof, pinions on said shafts having pitch circles extending within said channel, a pair of rack bars in said channel, one engaging one of said pinions and the other engaging the other, finger pieces extending from said rack bars for joint manipulation thereof, and resilient means for biasing said bars to move said finger pieces away from one another.

10. In a gage block, a circular aperture extending therethrough, a plane surface along one face thereof extending at right angles to the axis of said aperture, parallel blade-receiving grooves extending across said surface on either side of said aperture, a deep slot in said surface to one side of said aperture, and extending transversely of said grooves, a stub shaft traversing said slot 60 behind each blade groove, a guideway extending

across another face of said block, having an edge thereof extending substantially tangential to both said shafts, spiral gears within said slot on each of said shafts having pitch circles intersecting the base of the respective blade groove forwardly thereof, blades in said grooves having inclined rack teeth engaging said spiral gears, pinions on said shafts having pitch circles extending within said channel, a pair of rack bars in said channel, one engaging one of said pinions and the other engaging the other, finger pieces extending from said rack bars for joint manipulation thereof, and resilient means for biasing said bars to move said finger pieces away from one another.

11. In a gage of the type described, in combination, a pair of gage blocks, a circular aperture extending through each of said blocks, said blocks having facing plane surfaces along one face of each extending at right angles to the axis of their respective apertures, a rod extending through said apertures, and means for securing said blocks in position upon said rod, parallel blade-receiving grooves extending across the surface on either side of said aperture on one of said blocks, a deep slot in said last-named surface to one side of said aperture, and extending transversely of said grooves, a stub shaft traversing said slot behind each blade groove, a guideway extending across another face of said block, having an edge thereof extending substantially tangential to both said shafts, spiral gears within said slot on each of said shafts having pitch circles intersecting the base of the respective blade groove forwardly thereof, gaging blades having parallel edges lying in said grooves, one edge of which is adapted to engage the plane surface of the other block, and the other edge of which is provided with inclined rack teeth, pinions on said shafts having pitch circles extending within said channel, a pair of rack bars in said channel, one engaging one of said pinions and the other engaging the other, finger pieces extending from said rack bars for joint manipulation thereof, and resilient means for biasing said rack bars to move said finger pieces away from each other.
